Primary Examiner — Keith J Wilson(74) *Attorney, Agent, or Firm* — Muncey, Geissler, Olds & Lowe, P.C.(57) **CLAIM**

The ornamental design for a faucet spray head, as shown and described.

DESCRIPTION

FIG. 1 is a front perspective view of a faucet spray head according to the present invention.

FIG. 2 is a front view of the faucet spray head of FIG. 1.

FIG. 3 is a rear view of the faucet spray head of FIG. 1.

FIG. 4 is a left side view of the faucet spray head of FIG. 1.

FIG. 5 is a right side view of the faucet spray head of FIG. 1.

FIG. 6 is a top view of the faucet spray head of FIG. 1; and, FIG. 7 is a bottom view of the faucet spray head of FIG. 1. The dashed lines represent portions of a faucet spray head and form no part of the claimed design.

1 Claim, 7 Drawing Sheets(56)
